US00D330169S

United States Patent [19]

Yajima

[11] Patent Number: Des. 330,169

[45] Date of Patent: ** Oct. 13, 1992

[54] ELECTRONIC THERMOMETER

[75] Inventor: Akira Yajima, Suwa, Japan

[73] Assignee: Seiko Epson Corporation, Japan

[**] Term: 14 Years

[21] Appl. No.: 493,479

[22] Filed: Mar. 13, 1990

[30] Foreign Application Priority Data

Sep. 13, 1989 [JP] Japan 1-33553

[57] CLAIM

The ornamental design for electronic thermometer, as shown.

DESCRIPTION

FIG. 1 is a bottom, front and right side perspective view of an electronic thermometer showing my new design; FIG. 2 is a front elevational view;

FIG. 3 is a bottom plan view;

FIG. 4 is a rear elevational view;

FIG. 5 is a top plan view;

FIG. 6 is a left side elevational view; and,

FIG. 7 is a right side elevational view thereof.

FIG._1.

FIG._2.

FIG._6.

FIG._3.

FIG._4.

FIG._7.

FIG._5.
